Patented Dec. 18, 1917.

FIG. 1.

FIG. 2.

FIG. 2.

Inventor

Harry E. Shumway
By *Frank C. Curtis*
Attorney

UNITED STATES PATENT OFFICE.

HARRY E. SHUMWAY, OF WATERFORD, NEW YORK, ASSIGNOR TO VAN ZANDT, JACOBS & CO., OF TROY, NEW YORK, A CORPORATION OF NEW YORK.

SOFT FOLD-COLLAR.

1,250,524.

Specification of Letters Patent. Patented Dec. 18, 1917.

Application filed September 11, 1916. Serial No. 119,379.

To all whom it may concern:

Be it known that I, HARRY E. SHUMWAY, a citizen of the United States, residing at Waterford, county of Saratoga, and 5 State of New York, have invented certain new and useful Improvements in Soft Fold-Collars, of which the following is a specification.

Reference may be had to the accompanying drawing, and the reference characters marked thereon, which form a part of this specification. Similar characters refer to similar parts in the several figures therein.

The principal object of the invention is 10 to provide for the ready insertion within, and removal from, the band, of a soft fold-collar, of a stiffener-form adapted to hold the band in upright position in use, without adding to the number of plies of fabric 15 in the band at any point.

Other objects of the invention will appear in connection with the following description:

Figure 1 is a plan view of a soft fold-collar unfolded and opened out flat.

Fig. 2 is a plan view of the facing-ply for the outer side of the band provided with the buttonholed slits which permit the insertion and removal of the stiffener-form 30 when the collar is completed.

Referring to the drawings wherein the invention is shown in preferred form, 1, is the band; and 2, is the top attached to, and adapted to be folded over upon the band 35 in the usual manner. The band and the top are each formed of a plurality of plies of textile fabric.

The band is provided with the usual back buttonhole 3, and front buttonholes 4 and 5.

40 The plies of the band are inturned and secured together by stitching, 6, along the edge of the band in the usual manner.

In carrying out my invention I form in 45 the outer facing-ply, 7, of the band one or more buttonholed slits 8, which in the finished collar extend approximately from the lower edge-stitching, 6, to the upper edge-stitching, 6, of the band. These slits are cut and buttonholed in the facing-ply,

7, as shown in Fig. 2, before said ply is 50 incorporated in the band.

When the collar is completed the buttonholed slits, 8, are exposed on the outer side of the band where they are covered and concealed by the folded-over top. 55

The buttonholed slits, 8, afford entrance to pockets formed between the plies of the band at the respective ends of the band, into which pockets the respective ends of a suitable stiffener-form of celluloid or other 60 suitable material may be readily inserted.

The stiffener-form is thus held in place by said pockets and serves to hold the band in upright form in use.

Certain advantages of the construction 65 are the saving in expense due to utilizing the band-plies only in forming the pockets for the stiffener-form; and maintaining the band of uniform thickness throughout its length, which results in a more finished 70 product from the laundry, and in an uninterrupted upper edge of the band along its line of junction with the top.

I preferably employ two buttonholed slits, 8, said slits being located on opposite 75 sides of, and equidistant from the back buttonhole, 3.

The slits, 8, may be corded or a narrow reinforcing strip or patch of fabric, 9, may be applied to the inner side of the facing-ply, 7, at the points where the buttonholed slits, 8, are to be formed, the buttonholed slits being then formed through both the facing-ply and the reinforcing patch. 80

What I claim as new and desire to secure 85 by Letters Patent is—

A collar having a member formed of a plurality of plies of fabric, one facing-ply of said member being provided with a buttonholed slit extending approximately from 90 the top to the bottom of said member, and having a patch applied to the inner side of said facing-ply, said buttonholed slit extending through both the facing-ply and the patch. 95

In testimony whereof, I have hereunto set my hand this 8th day of September, 1916.

HARRY E. SHUMWAY.
